CONTAINER

Julian Maas, St. Louis, Mo.

Application May 19, 1938, Serial No. 208,783

7 Claims. (Cl. 229—54)

This invention relates generally to containers and, more particularly, to a certain new and useful improvement in containers of bag type for the carrying of merchandise and the like.

5 My invention has for its primary objects the provision of a container of the type mentioned which is simple in structure, which may be readily and economically manufactured, which may be conveniently securely closed without the employment of tying strings or other such foreign means, which, when closed, is substantially secure against accidental opening, and which is highly efficient in the performance of its stated functions.

15 And with the above and other objects in view, my invention resides in the novel features of form, construction, arrangement, and combination of parts presently described and pointed out in the claims.

20 In the accompanying drawings (2 sheets)— Figure 1 is a perspective view of an open container or bag constructed in accordance with and embodying my invention;

25 Figures 2 and 3 are perspective views, illustrating the container or bag of Figure 1 with its flaps in partially closed and fully closed positions, respectively;

30 Figure 4 is a detail sectional view of the bag, taken approximately along the line 4—4, Figure 3;

Figure 5 is a fragmentary perspective view of a modified container or bag also embodying my invention;

35 Figure 6 is a detail sectional view of the modified bag of Figure 5, illustrating the bag with its flaps in fully closed position;

40 Figures 7 and 8 are fragmentary rear and front perspective views, respectively, of a second modified form of container or bag embodying my present invention, illustrating the closure flaps of the bag in open and partially closed positions, respectively;

45 Figure 9 is a detail sectional view of the bag of Figures 7 and 8, illustrating the walls and flaps of the bag in fully closed position;

50 Figures 10 and 11 are fragmentary perspective views of a third modified form of bag embodying my present invention, showing the flaps of the bag or container in open and partially closed positions, respectively;

Figure 12 is a detail sectional view of the bag or container of Figures 10 and 11, taken approximately along the line 12—12, Figure 10;

55 Figures 13 and 14 are fragmentary perspective views of a fourth modified form of container

or bag embodying my present invention, illustrating the flaps of the container in open and partially closed positions, respectively;

Figures 15 and 16 are detail sectional views, taken, respectively, approximately along the line 5 15—15, Figure 13, and the line 16—16, Figure 14;

Figures 17 and 18 are fragmentary perspective views of a fifth modified form of container or bag embodying my present invention, illustrating the flaps of the container in open and 10 partially closed positions, respectively; and

Figure 19 is a detail sectional view, taken approximately along the line 19—19, Figure 18.

Referring now in more detail and by reference characters to the drawings, which illustrate 15 practical embodiments of my invention, A designates a container or bag constructed preferably of paper, fabric, or any other suitable material in any desired shape and according to any conventional process. 20

As illustrated, the bag or container A comprises similarly shaped registering front and back walls or panels 1, 2, marginally joined or connected throughout except at their upper transverse margin, where the panels 1, 2, are flexibly 25 separate in the provision of a container opening or mouth 3, the walls 1, 2, being further provided adjacent the mouth 3 with registering suitably elongated preferably oval apertures 4, all as best seen in Figures 1, 2, and 3, and for 30 purposes presently more fully appearing.

The back wall or panel 2 is further provided at its upper margin with a preferably integral flap-extension 5 foldable on a hinge or score-line 6 and being cut away centrally of its free margin 35 in the provision of a recess 7 complementary in shape to the apertures 4 in such manner that, when the flap 5 is folded in bag-closing position about the hinge or score-line 6 forwardly and downwardly over the front wall or panel 1, the 40 recess 7 will unobtrusively register marginally with the apertures 4, as best seen in Figure 2.

Adhesively or otherwise permanently secured flatwise to and upon the outer face and suitably adjacent the upper margin of the front wall or 45 panel 1, is a preferably oblong rectangular tab-section 8 preferably integrally extended to include a bag-closure flap 9 foldable on a score or hinge-line 10 and formed within its area with a cut-out or aperture 11 for registration with the 50 wall-aperture 4 when the flap 9 is in bag-closing position, as best seen in Figures 3 and 4.

The flap 9 is further provided on its inner or under face with a coating 12 of suitable adhesive, such as, for instance, latex. The back-wall flap 55

5 is also preferably provided co-operably on a portion of its outer face, as shown in Figure 2, with a coating 13 of latex or other adhesive for underlying registration with the flap-coating 12 5 when the closure-flap 9 is folded upwardly and downwardly into bag-closing position.

Accordingly, in use, on the container or bag A being suitably filled, the flap 5 is first folded over and downwardly upon the wall 1 into bag-closing position. The closure flap 9 is then folded upwardly and pressed downwardly upon the latex or adhesive coating 13 of the flap 5. The coatings 12 and 13 are then adhesively forced together or merged, thereby separably securing the flaps 5 15 and 9 in tight closure-forming engagement over the mouth 3 of the bag A, as best seen in Figures 3 and 4. Whenever it is desired to open the bag A, the flap 9 may be pulled upwardly from adhesive engagement with the underlying flap 5, 20 the securing latex-adhesive film being readily ruptured or broken, and the flap 5 then reversely folded for completely opening the bag-mouth 3. Such opening operation may thus be very quickly and conveniently accomplished without tearing 25 or damaging the bag A or lessening its useful life, the bag A being subsequently closed and resealed in substantially the same manner for further repeated use, if desired. And it will be observed that, when the flaps 5 and 9 are co-operably in 30 bag-closing engagement, as described, the apertures 4 and 11 are in full registration and provide a convenient hand-grip for ready portability of the bag A and its contents.

The modified container or bag A' of Figures 5 35 and 6 is similar in all respects to the described container or bag A and hence its parts are similarly designated, except that an adhesive coating is omitted from the flap 5, the closure-flap 9 being adhesively engageable in bag-closing position 40 with the flap 5 and the bag A' being otherwise closed and opened in substantially the same manner as the described container or bag A.

The modified container or bag A² of Figures 7, 8, and 9 is also similar in all respects to the 45 described bags A and A', except that the back panel or wall 2^a is provided flatwise with a reinforcing-strip 14 of substantially the same width as the closure-forming tab 8 and flap 9. Such reinforcing-strip 14 is provided within its area 50 with an aperture 15 of the same registering shape and contour as the handle-forming apertures 4, 11, and has a length to extend over the outer face of the closure flap 5^a for foldable bag-closing movement therewith, the strip 14 being provided 55 on its outer face with a latex or other adhesive coating 13^a for adhesive securing engagement, when the flap 5^a is in bag-closing position, as best seen in Figure 8, with the coating 12 of the front flap 9.

60 A³ designates another modified form of bag embodying my present invention, which is substantially identical with the bag A, except that the latex coated closure flap 5^b is initially folded backwardly upon itself, as shown in Figure 12, 65 for the greater protection of the latex coating 13^b. When the bag A³ is filled and ready for closure, the flap 5^b is first folded outwardly away from the outer face of the back wall 2^b and then folded downwardly in closure formation across 70 the upper margin of the front wall 1^b and adhesively secured in full bag-closure position with the adhesive coating 12^b of the locking flap 9^b.

A⁴ designates still another modified form of bag embodying my present invention. This form is 75 substantially similar to the container or bag A,

the bag A⁴ comprising a rear or back wall 2^c provided with a latex-coated closure flap 5^c and a front wall 1^c having a closure flap 9^c, the front and back walls 1^c, 2^c, and the closure flap 9^c being similarly provided with registering handle-forming apertures 4^c, 11^c, respectively. The closure flap 5^c is provided at its free margin with a pair of parallel outwardly extending tabs 16 each provided on its under face with a latex coating 13^c and normally, as when the bag is open, 10 folded backwardly into flat facewise engagement with the outer face of the flap 5^c for the greater protection of their latex coating 13^c, as best seen in Figure 13. When the bag A⁴ is suitably filled and ready for closing, the tabs 16 are first folded 15 upwardly or backwardly away from the outer face, and to extend in the plane, of the flap 5^c. The closure flap 5^c and the associated extension tabs 16 are thereupon folded forwardly and downwardly into bag-closure position over the front 20 panel 1^c and the flap 9^c then folded upwardly and pressed, in full bag-closure position, into adhesive engagement therewith, all as best seen in Figures 14 and 16.

A⁵ designates a further modified form of container or bag embodying my present invention, which also is substantially similar to the bags A² and A⁴, except that the reinforcing strip 14^d has a pair of extension-tabs 17 shaped for co-operation, and to extend in overlying registration, with the flap-extensions 16^d. The rearwardly presented face of each of the extension tabs 17 is provided with a latex coating 13^d and, together with the extension tabs 16^d, are normally folded backwardly and downwardly over the rearwardly presented face of the closure flap 5^d for the greater protection of the latex coating 13^d. When the container A⁵ is suitably filled and ready for closing, the extension tabs 17 and the associated tabs 16^d are first folded upwardly to extend in substantially the plane of the closure flap 5^d, which is then folded downwardly in closure-formation across the mouth 3 and over the outer face of the front panel 1^d. The flap 9^d is then folded upwardly and downwardly into 45 adhesive bag-closure engagement with the coated reinforced extensions or tabs 17, as indicated in Figure 17.

The bag or container in all its several forms 50 may be inexpensively constructed and is exceedingly efficient and convenient in the performance 55 of its intended functions.

It should be understood that other changes and modifications in the form, construction, arrangement, and combination of the several parts of 60 the bag may be made and substituted for those herein shown and described without departing from the nature and principle of my invention.

Having thus described my invention, what I 65 claim and desire to secure by Letters Patent 70 is—

1. A bag having connected co-operable mouth-providing front and rear walls, a first closure-flap on the free margin of said rear wall foldable closure-wise over and across said mouth, a second closure-flap on, and adjacent the free margin of, said front wall, said walls and second flap having apertures registering one with the other when said flaps are in bag-closure engagement in the formation of a hand-grip, and a reinforcing strip having a width somewhat greater than the length of said aperture and being secured upon the outer face of the rear wall and extending longitudinally thereacross and across the rear wall flap, said reinforcing strip being 75

- 5 further provided with apertures in registration with the wall and flap apertures and being adapted for securing engagement at its outer end beneath the second flap when the first flap is in bag-closure position.
- 10 2. A bag having connected co-operable mouth-providing front and rear walls, a first closure-flap on the free margin of said rear wall foldable closure-wise over and across said mouth, a reinforcing strip mounted on the outer face of the rear wall adjacent the upper margin thereof and extending integrally across the upper margin thereof and across the first closure flap, and a second closure-flap on, and adjacent the free margin of, said front wall adapted for overlying registration with the outer portion of said reinforcing strip when in bag-closure position, said flaps having co-operably engaging adhesive coatings.
- 15 20 3. A bag having connected co-operable mouth-providing front and rear walls, a first closure-flap on the free margin of said rear wall foldable closure-wise over and across said mouth, a reinforcing strip mounted on the outer face of the rear wall adjacent the upper margin thereof and extending integrally across the upper margin thereof and across the first closure flap, and a second closure-flap on, and adjacent the free margin of, said front wall adapted for overlying registration, and having an adhesive coating for securing engagement, with the outer portion of said reinforcing strip when in bag-closure position.
- 25 30 35 40 4. An envelope including connected co-operable mouth-providing front and rear walls, a first closure-flap on the free margin of said rear wall foldable closure-wise over and across said mouth and the free margin of the front wall into flat abutment along its under face with the outer face of the front wall, said flap having a plurality of outwardly extending tabs, and a second closure-flap hingedly mounted on the outer face of the front wall for bag-closing engagement
- 5 along its under face with the outer face of the first flap and said tabs.
- 10 15 20 25 30 35 40 5. An envelope including connected co-operable mouth-providing front and rear walls, a first closure-flap on the free margin of said rear wall foldable closure-wise over and across said mouth and the free margin of the front wall into flat abutment along its under face with the outer face of the front wall, said flap having a plurality of outwardly extending tabs adhesively coated on their outer face, and a second closure-flap hingedly mounted on the outer face of the front wall for bag-closing engagement along its under face with the outer face of the first flap and said tabs.
- 10 15 20 25 30 35 40 6. An envelope including connected co-operable mouth-providing front and rear walls, a first closure-flap on the free margin of said rear wall foldable closure-wise over and across said mouth and the free margin of the front wall into flat abutment along its under face with the outer face of the front wall, said flap having a plurality of outwardly extending tabs adhesively coated on their outer face, and a second closure-flap hingedly mounted on the outer face of the front wall and provided on its under face with an adhesive coating for bag-closing engagement with the adhesively coated face of said tabs.
- 10 15 20 25 30 35 40 7. An envelope including connected co-operable mouth-providing front and rear walls, a first closure-flap on the free margin of said rear wall foldable closure-wise over and across said mouth and the free margin of the front wall into flat abutment along its under face with the outer face of the front wall, said flap having a plurality of outwardly extending tabs adhesively coated on their outer face and initially folded back upon the first flap for normally protecting said coating, and a second closure-flap hingedly mounted on the outer face of the front wall and provided on its under face with an adhesive coating for bag-closing engagement with the adhesive coating of said tabs.

JULIAN MAAS.
